UNITED STATES PATENT OFFICE.

HEINRICH BOCKISCH, DECEASED, LATE OF POUGHKEEPSIE, NEW YORK; BY GEORGE W. GITTINS, ADMINISTRATOR, OF NEW YORK, N. Y., ASSIGNOR TO WELTE-MIGNON CORPORATION, OF NEW YORK, N. Y., A CORPORATION OF NEW YORK.

NOTE SHEET FOR AUTOMATIC MUSICAL INSTRUMENTS.

Application filed April 21, 1920. Serial No. 375,577.

To all whom it may concern:

Be it known that HEINRICH BOCKISCH, deceased, late a citizen of the Republic of Czechoslovakia, and formerly residing at 5 Poughkeepsie, in the county of Dutchess and State of New York, United States of America, invented certain new and useful Improvements in Note Sheets for Automatic Musical Instruments, of which the following is a specification.

This invention relates to note sheets for automatic musical instruments having two or more devices for producing different musical effects.

15 The primary object of this invention is the provision of a note sheet having perforations in a single line which may control a plurality of devices operable singly or collectively to produce different musical effects.

20 A particular object of this invention is to provide a note sheet having perforations which will cause to operate two stop mechanisms of an automatic organ, and put either one or both on or off at will, the perforations being in a single line in the note sheet. A mechanism with which this sheet will operate to produce the result stated, is described in the applications (Cases A and B) of Heinrich Bockisch and executed of 25 even date herewith and filed in the United States Patent Office on April 21, 1920, Serial Numbers 375,575 and 375,576 Patent No. 1,440,763 dated January 2, 1923, respectively.

30 Referring to the drawing, the figure represents a plan view of a note sheet, embodying my invention, and showing the perforations for controlling the two devices for causing different musical effects such as two stops of an automatic organ. The sheet is represented as passing in a direction from the upper to the lower roll of the winding mechanism, as indicated by the arrow. The perforations for controlling the stop mechanism are shown in a single line at the right of the sheet, although it is to be understood that the particular placing of the perforations at one side of the other has nothing to do with this invention as long as 35 the duct in the tracker with which they are to register is correspondingly placed. In the form of sheet illustrated in the drawings, the note perforations would be placed at the left of the perforations illustrated,

and in that part of the sheet which is shown 55 clear. The perforations of music have been omitted from the drawings since they, themselves, form no part of the present invention.

In the drawings, 10 designates the tracker having a tracker duct 11, therein. 12 designates the sheet which is shown as being broken because the space between the perforations is indeterminate except in the particular piece of music in which the perforations are made.

As the sheet passes over the tracker 10 the duct 11 is opened by a hole 13 in the sheet 12. This perforation only opens the duct 60 an instant. This impulse of air admitted to 70 the duct 11, affects a mechanism which is functionally responsive to such an impulse and is on the same pneumatic line with another mechanism which is not functionally responsive to such an impulse, but which is 75 functionally responsive to an impulse of different characteristic as one of long duration. The mechanism is so constructed that changes in the musical effect do not occur during the time when the perforations 80 are not registered with the duct. The change brought about by the short impulse of the opening 13 is maintained until the perforation 14 opens the duct 11. The mechanisms are so constructed that successive impulses 85 of the same characteristics operate the stops in opposite ways. For instance the perforation 13 causes the short impulse mechanism to come "on" while the succeeding perforation 14 will cause it to be taken "off." The 90 mechanism is now in the same condition as before the perforation 13 opened the duct 11.

When the perforation 15^a opens the duct 11, the mechanism which is more quickly responsive operates. Before, however, it can 95 cause any change in the musical effect, the duct 11 is closed and the perforation 15^b opens it. The latter operates to take off the mechanism put on by the perforation 15^a, also since it is a longer perforation than the perforation 15^a, the impulse is longer and the mechanism which is sensitive to long impulses operates to perform its function. Thus, we have the mechanism which is responsive to a short perforation "off" and that responsive to a long perforation "on." These mechanisms remain in this condition 100 until the perforation 16^a reaches the tracker 105

duct 11. Since the perforation 16^a is a short one the mechanism responsive to an impulse from such a perforation, immediately comes on. The perforation 16^b however immediately registers with the duct 11, and the first part of the impulse caused by the perforation 16^b takes it off again. However, as the perforation is a long one the other mechanism has time to become functionally operative and bring the second mechanism to the "off" condition.

It has been shown above how it was possible by this sheet to operate either mechanism on or off from the single line of perforations. I will now describe the perforations for causing both mechanisms to come "on" at substantially the same time and also to go "off" at substantially the same time.

When the perforation 17 uncovers the duct 11, the first mentioned mechanism operates to perform its function. Since the perforation does not immediately close, the other mechanism operates to perform its function in the musical composition. Both mechanisms are now operating.

As the perforation 18 uncovers the duct 11, the reversing portions of the respective mechanisms operate in a similar manner to take both mechanisms "off."

A very useful application of this invention is to the sheet used with an automatic pipe organ which may have many stops. In this case one line of perforations may be used to put on and off each two stops. In this way great saving is made in the width of the sheet.

While this invention is described in connection with an automatic organ having two stops, I desire to have it understood that it is of broader application and may be used for expression devices on automatic musical instruments generally.

It is also to be understood that while a single line of perforations is shown in the drawing, it is intended to have one line of perforations for each two stops of the instrument.

It is understood that modifications and changes in the proportions and form of the perforations described may be made without departing from the spirit of the invention and within the scope of the appended claims.

Having described my invention what I claim is:

1. A note sheet having a line of perforations to control two mechanisms for the production of different musical effects, said line of perforations comprising perforations

of one area to control the putting in operation of one of the mechanisms and perforations of the same area for putting out of operation the same mechanisms and perforations of different area to control the putting in and putting out of operation of both of the mechanisms.

2. A note sheet having a line of perforations to control two mechanisms for the production of different musical effects, said line of perforations comprising perforations of one length to control the putting in operation of one of the mechanisms and perforations of the same length for putting out of operation the same mechanisms and perforations of different length to control the putting in and putting out of operation of both of the mechanisms.

3. A note sheet having a line of perforations to control two mechanisms for the production of different musical effects, said line of perforations comprising comparatively short perforations to control one of the mechanisms, adjacent short and long perforations for putting in or out of operation only the other mechanism and long perforations for controlling both mechanisms.

4. A note sheet having a line of perforations to control two mechanisms for the production of different musical effects, said line of perforations comprising short perforations to cause one of the mechanisms to be put into operation, other short perforations to cause the same mechanism to be put out of operation, long perforations to cause both of the mechanisms to be put into operation, and other long perforations to cause both of the mechanisms to be put out of operation.

5. A note sheet having a line of perforations to control two mechanisms for the production of different musical effects, said line of perforations comprising short perforations to cause one of the mechanisms to be put into operation, other short perforations to cause the same mechanism to be put out of operation, long perforations to cause both of the mechanisms to be put into operation, other long perforations to cause both of the mechanisms to be put out of operation, and still other long perforations to cause one of the mechanisms to be put out of operation, and the other mechanism to be put into operation.

In testimony whereof I affix my signature.

GEO. W. GITTINS,
Administrator of the Estate of Heinrich Bockisch, Inventor, Deceased.
